UNITED STATES PATENT OFFICE.

LANGDON CASKIN, OF HAVERFORD, PENNSYLVANIA.

DISHWASHING APPARATUS.

Application filed December 22, 1925. Serial No. 77,086.

This invention relates to improvements in dish washing apparatus.

The primary object of this invention is the provision of improved dish washing apparatus embodying a novel assemblage whereby to enable the facile washing of dishes in a continuous operation, without the interruption of emptying and filling of the different parts of the apparatus.

10 A further object of this invention is the provision of improved dish washing apparatus embodying an improved arrangement of trough, spray chamber, and drying table, with the same relatively positioned and constructed to facilitate the passing of dishes therealong during the washing operation, and to permit the drain of all water into the trough and from thence to any suitable location.

15 20 A further object of this invention is the provision of a novel spray receptacle for dish washing apparatus.

A further object of this invention is the provision of novel dish washing apparatus embodying improved water dispensing and drain means therefor.

25 Other objects and advantages of this invention will be apparent during the course of the following detailed description.

30 In the accompanying drawings, forming a part of this specification, and wherein similar reference characters designate corresponding parts throughout the several views,

35 Figure 1 is a longitudinal sectional view taken through the improved dish washing apparatus, showing the novel cooperation of parts with a tray of dishes in the spray chamber thereof.

40 Figure 2 is a plan view of the apparatus with parts thereof removed to show the details thereof.

45 Figure 3 is a sectional view taken through the improved apparatus substantially on the line 3—3 of Figure 1.

50 Figure 4 is a sectional view taken through the apparatus substantially on the line 4—4 of Figure 1.

55 Figure 5 is a sectional view taken through the improved apparatus looking downwardly upon the same, showing the spray chamber in section with trays of dishes as they appear during operation of the washing apparatus.

60 Figure 6 is a reduced plan view of the

drain table of the apparatus as used with 55 a trough, with the spray receptacle removed.

Figure 7 is a perspective view of a novel type of track and dish supporting platform for the spray receptacle of the improved dish washing apparatus.

60 In the drawings, wherein for the purpose of illustration is shown only a preferred embodiment of this invention, the letter A may generally designate the improved dish washing apparatus which may comprise a 65 trough or tub B; table C; spray receptacle D; and water dispensing fixtures E associated with the parts of the apparatus.

The trough or tub B is preferably of any 70 approved construction, although preferably of elongated character, including a bottom wall 10; end walls 12; and side walls 13 and 14. The same provides a relatively deep

compartment 15, and a drain conduit 16 is connected in the bottom wall 10, and leads to 75 any suitable place, such as a sewer, the same preferably having a trap 17 therein adjacent the trough B. At the juncture of the drain conduit 16 and the wall 10, a socket 18 is

provided adapted to detachably receive an 80 overflow control pipe 19 which may fit in the socket 18 to act as an extension for the conduit 16, a passageway 20 thereof being open at the top edge thereof, and the top edge 23 being located below the upper edges 85

of the side and end walls 12, 13 and 14, as is illustrated in the drawings, so that the head of water in the compartment 15 will be 90 relatively high, during dish washing operation, although merely by removal of the overflow extension 19 the entire body of water in the compartment 15 may drain thru the conduit 16.

95 It is preferred to provide a dish supporting tray 25 in the compartment 15 immediately over the floor or bottom 10 thereof, upon which the dishes may rest as a protection therefor against breaking when they drop into the trough for the initial cleaning operation.

100 Referring to the construction of the drain table C, the same preferably includes a table board or platform 27, supported in any approved manner by legs 28. The table body 27 is constructed to provide an opening 29 extending to one end thereof, in which opening 29 the spray receptacle D is received, as will be subsequently set forth. The drain

table body 27 includes the drain and drying portion 30, extending from the inner end of the opening 29 to the outer edge 31 of the table, upon which dishes pass in the final 5 operation to dry and drain. The table body 27 at opposite sides of the opening 29 has drain ways or side extensions 31 and 32, which at the free edges thereof are provided with anchoring lips or extensions 35, down- 10 turned, as is clearly illustrated in the drawings, for engaging over the upper edge of the side wall 13 of the trough B, in order to anchor and support this end of the drain table on the trough B. It is to be noted that 15 the opening 29 has an entrance at the end of the table where the lips are formed, and the longitudinal edges 37 of this opening 29 are beveled in downwardly converging relation to support the oval-shaped spray re- 20 ceptacle body as will be subsequently described. The table platform 27 is provided with a lip extension 38 which projects into the opening 29 at the inner end thereof, and which is likewise adapted to project into 25 the compartment 40 of the spray receptacle D, and has a bevelled edge 39^a. The table C is so mounted by the legs 28 that it slopes from the edge 31 downwardly at a gradual incline towards the trough B, in order that 30 water may drain from the table drying portion 30, along the ways 31 and 32 and thence into the trough compartment 15, as can readily be understood. The table body 27 along the opposite longitudinal edges there- 35 of is provided with guard rails or rims 42, projecting upwardly of the plane of the upper surface of the table body 27, for the entire length thereof, in order to prevent lateral drip or drain of water from the table body 27.

As is illustrated in Figure 1 of the drawings, any of the legs 28 of the apparatus may be provided with suitable brackets 45 for supporting the trough B. In lieu thereof, 45 the trough B may be provided with independent leg supporting means.

Referring to the spray receptacle D, the same in cross section is preferably oval, including the oval shaped body 45, with front 50 and rear preferably flat end walls 46 and 47, respectively having entrance and exit openings 48 and 49 therein. The openings 48 and 49 are preferably square, and the former opening is provided with closure doors 50, hingedly connected by spring hinges 51 at the opposite side edges thereof, the tendency of the spring hinges being such as to maintain the doors 50 shut to close the opening 48, and prevent splashing of water from 55 the compartment 40. In similar manner the opening 49 is provided with a pair of closures 52 hingedly connected by spring hinges 53 at opposite side edges of said opening 49, the spring hinges 53 urging the 60 doors or closures 52 into a shut position to

close the opening 49. It should be noted that the lower edges of the doors 50 and 52 are spaced slightly above the lower edges of the openings 48 and 49.

The receptacle D is adapted to be placed 70 in the opening 29 of the table body 27, and in this position the sloping side walls of the body 45 of the receptacle rest upon the beveled edges 37 facing the opening 29. The lip 38 of the table enters the opening 49 just below the doors 52, so that said lip 38 really projects into the compartment 40 of the spray receptacle D, to aid in supporting the rack 55 upon which the dishes slide 75 in their travel through the spray compartment 40.

At the front end of the receptacle D, a drain and supporting lip 57 is downturned from the wall 46 of the receptacle D, the same being disposed below the doors 50, to engage over the top edge of the trough wall 13, as an aid in support of the receptacle D, and to enable proper drain of the water into the trough, and prevent leaking 90 of the same from the apparatus. The supporting lip 57 is continuous with the supporting lips 38 of the table C, above mentioned, and as illustrated in Figure 3 of the drawings they provide an effective seal for the drain of water past the juncture between 95 the table C and the trough B, as well as between the receptacle D and the trough B.

The spray receptacle D is so supported that the slope of the bottom thereof is from the dish drying portion 30 of the table body 100 27 towards the trough B, and adjacent the trough B a drain conduit or opening of any suitable character, such as shown at 60 in Figure 1 of the drawings, may be provided, having connection with the trough compartment 105 15 for drain of water thereinto from the receptacle compartment 40.

The slide tray 55 is horizontally supported within the compartment 40, the same comprising a plurality of parallel spaced strips 62, connected at one end by means of a cross piece 63, and they may support at their opposite ends lateral pieces 64. It is to be noted that the ends of these strips 62 project beyond the cross 115 piece 63, and the ends adjacent the cross piece 63 rest upon the lower edge of the door opening 48, whereas the opposite free ends rest upon the projecting lip 38 of the table platform 27, as illustrated in Figure 120 of the drawings. The cross piece 63 may abut the inside surface of the front wall 46 of the receptacle D, to prevent movement of the tray 55 towards the trough B, and the side pieces 64 may abut against the wall 47 125 to prevent sliding movement of the tray 55 away from the trough B. The plane of the upper surface of the tray 55 is slightly above the plane of the supporting table 27, so that dishes may be readily slid over the tray 55, 130

thru the door opening 49, and onto the receiving portion 30 of the table body 27. The baskets G have lugs 64^a which project into the spaces between bars 62, to guide the 5 baskets and support them on the drain table.

Referring to the plumbing fixtures E, hot and cold water supply cocks 70 and 71 are provided for the trough B, adjacent the end wall 12, and a lateral pipe 72 extends from 10 the hot water pipe 73, and is connected by a suitable fitting 74 in a vertical conduit 75. Suitable upper and lower horizontal conduits 76 and 77 extend from the upper and lower ends of the vertical conduits 75, and 15 have spray connections in the compartment 40 substantially midway between the end walls 46 and 47 thereof. In the conduit 72 adjacent the hot water cock 70 is placed a suitable control valve 78 for regulating the 20 supply of hot water to the hot water sprays in the receptacle compartment 40. Within the compartment 40, the conduit 76, which enters the same, is provided with a cross conduit 80, which at the ends thereof is provided with 25 spaced sprays 81 and 82, facing in a converging relation towards the tray 55. The lower conduit 77 is provided with a cross conduit 83 just below the receptacle D, extending longitudinally thereof, and at its ends 30 being upturned and providing vertical sprays 85 and 86 in the lower portion of the compartment 40, below the tray 55. The single valve 78 controls the spray of hot water through all of the sprays 81, 82, 85 35 and 86, and hot water may be supplied to the spray receptacle D independent of hot water supply to the trough B.

From the foregoing description of this invention it is apparent that a novel type of 40 dish washing apparatus has been provided in which the trough; spray cabinet; and drying table have been so relatively positioned as to enable the continuous operation of washing dishes to take place, with facility 45 and with efficiency. The initial cleansing operation takes place in the trough B, and the dishes are preferably handled in wire baskets G. As they are lifted from the trough B they are put into the spray cabinet 50 compartment 40 thru the swinging doors 50, and they readily enter the same and are placed between the upper and lower sets 55 of sprays so that the dishes thereof arranged therein are individually sprayed and cleansed. The successive baskets are pushed 60 into one end of the spray receptacle or cabinet D, and succeeding baskets push the same along the rack or tray 55, which acts as a track, and the baskets of dishes are finally 65 forced thru the exit doors 52, onto the drain and drying portion 30 of the platform 27. The drain of all water during the entire procedure is into the trough compartment 15; the water from the spray cabinet draining 70 thru the conduit 60 and the water from the

drain table C draining from the drying portion 30 along the side portions 31 and 32 which act as troughs therefor, and the water passes over the lips 35 into the trough compartment 15, as is readily obvious. The 70 operation is continuous and during the washing procedure the dishes are thoroughly cleansed, sprayed, and dried. Due to the fact that the overflow extension 19 is provided, the grease will float into the same, 75 and the lower body of water remains comparatively clean to effect the initial cleansing operation in the trough B. Thus the drain keeps the water refreshed. The spray chamber is protected by reason of the swinging doors, and if desired single baskets of 80 dishes may be placed, as illustrated in Figure 1.

Various changes in the shape, size, and arrangement of parts may be made to the 85 form of invention herein shown and described, without departing from the spirit of this invention or the scope of the claims.

I claim:

1. Dish washing apparatus comprising a 90 trough, drain means for the trough, a spray cabinet, having a bottom, a tray for the spray cabinet disposed in a plane substantially above the said bottom and the trough, said spray cabinet having an entrance opening 95 adjacent the trough and facing the same and an exit opening at its opposite end aligning with the entrance opening and likewise disposed above said tray, means for spraying water in said cabinet upon articles 100 passing therethrough, a table outwardly of the exit opening of the spray cabinet for receiving dishes as they exit from said exit opening, said table and spray cabinet bottom inclining towards and each directly extending to the trough for drain of water 105 thereinto.

2. In dish washing apparatus of the class described the combination of a trough, a table including a dish receiving drying portion and spaced drain extensions resting at their ends remote from the dish receiving portion upon said trough, a spray receptacle mounted in the space between said drain extensions of the table, said spray receptacle 110 having an entrance opening adjacent said trough and an exit opening facing said dish receiving portion of the table, and spray means in said spray receptacle. 115

3. Dish washing apparatus comprising a 120 trough, drain means for the trough, a table comprising a dish receiving portion and spaced extensions having lips at the ends thereof, said spaced extensions at the lips being adapted to engage over the trough, 125 a spray cabinet mounted in the space between said table extensions having an entrance opening at one end thereof facing the trough immediately adjacent the same and located thereabove and an exit opening fac- 130

ing the dish receiving table portion and in alignment with the entrance opening.

4. Dish washing apparatus comprising a trough, drain means for the trough, a table comprising a dish receiving portion and spaced extensions having lips at the ends thereof, said spaced extensions at the lips being adapted to engage over the trough, a spray cabinet mounted in the space between said table extensions having an entrance opening at one end thereof facing the trough immediately adjacent the same and located thereabove and an exit opening facing the dish receiving table portion and in alignment with the entrance opening, spray means in the cabinet for transversely spraying water between said entrance and exit openings, and a removable tray mounted in the cabinet in alignment between the entrance and exit openings and in substantially the same plane with the dish receiving table portion.

5. Dish washing apparatus of the class described comprising a trough, a table providing a dish drying portion having spaced extensions projecting beyond an end thereof with the free ends of said extensions resting on an upper edge of said trough, with said dish receiving portion and extensions sloping towards the trough for drain of water therealong into the trough, said table receiving portion having a lip thereon projecting into the space between said spaced extensions, a spray cabinet mounted in the space between said spaced extensions having an entrance opening in one end and disposed above and adjacent to the trough and an exit opening aligning with the entrance opening at the opposite end of said cabinet disposed adjacent to and above the dish receiving portion of the table, the lip of said dish receiving portion of the table extending into said exit opening into the compartment of said cabinet, a removable tray in the compartment of the cabinet at one end resting on the

edge of the entrance opening of the spray cabinet and at the opposite end resting on the lip of the table which projects into said compartment at the exit opening of the cabinet, and hot water spray means in said cabinet above and below the removable tray.

6. In dish washing apparatus the combination of a table having an opening therein, a spray receptacle supported by the table in said opening, with a part of the receptacle extending below the table top surface, said spray receptacle being open at opposite ends thereof, spray means in the receptacle below the level of the top surface of said table, and a removable dish supporting tray in the receptacle extending between said openings and slightly above the top surface of said table.

7. In dish washing apparatus a spray receptacle comprising a body having a compartment therein and end walls with openings therein, a spray in the bottom portion of the compartment of said body, and a removable tray in the spray compartment between said openings comprising a cross strip at one end to which are connected a plurality of longitudinally extending supporting pieces, the cross strip being adapted to rest against one end wall with the cross pieces at their ends resting on an edge of said end wall in the opening of said end wall, the outermost longitudinal pieces of the tray having outturned ends, and a table upon which the tray is to be supported having a portion extending thru the opening of the end wall opposite that opening immediately above mentioned upon which the free ends of the longitudinal pieces of the tray rest, the outturned ends of the side longitudinal pieces of the tray being in engagement with the inner surfaces of the adjacent end wall to prevent displacement of the tray thru the end wall opening.
